UNITED STATES PATENT OFFICE.

MATTHEW RUSSELL BERGER, OF PHILADELPHIA, PENNSYLVANIA.

EAVES-TROUGH SHANK.

Application filed April 14, 1923. Serial No. 631,995.

To all whom it may concern:

Be it known that I, MATTHEW RUSSELL BERGER, a citizen of the United States, residing at the city of Philadelphia, in the county 5 of Philadelphia and State of Pennsylvania, have invented certain new and useful Improvements in Eaves-Trough Shanks, of which the following is a specification.

This invention, generally stated, relates 10 to eaves trough hangers and has more especial relation to the shanks therefor.

A common form of shank, as at present manufactured, is made of channel iron with the angles or flanges of that portion of the 15 shank adapted for engagement beneath the roof shingles, partially removed, usually by means of a shearing operation. Primarily such shearing operation requires considerable time; must be carefully done; and eliminates a portion of the "stock" forming the shank. Secondarily, when securing shingles over such sheared shank ends, practice 20 dictates that, the shingles frequently split, particularly if the shearing has left an unequal distribution of angles or flanges, and further, a shank end is not easily caused to 25 engage beneath a shingle.

The leading object of the present invention is to overcome the above described disadvantages and provide a construction of shank in which the shearing of shank angles or flanges is eliminated thereby requiring no "stock" to be taken 30 from the shank, the flanges according to the present invention being flattened or squeezed by a press at that end adapted to lie beneath roof shingles, thereby reducing the cost of manufacture; speeding up production; providing a tapered end for ready 35 insertion beneath shingles; and reducing the possibility of splitting shingles when nailing same in place over a shank. With these and other objects in view the invention consists of the improvements herein- 40 after described and finally claimed.

The nature, characteristic features and scope of the invention will be more fully understood from the following description taken in connection with the accompanying 45 drawings forming part hereof, and in which:

Fig. 1, is a view in plan of channel iron prior to the presentation thereof to a press.

Fig. 2, is an end view thereof.

Fig. 3, is a diagrammatic view of the 50 manner of forming the shank end in accordance with the present invention.

Fig. 4, is a view in side elevation of the shank after the press operation.

Fig. 5, is a top or plan view thereof.

Fig. 6, is a view in cross-section taken 60 upon the line 5—5 of Fig. 5.

Fig. 7, is an elevational view of the completed shank, and

Fig. 8, is a fragmentary view in elevation illustrating a shank embodying the invention as applied beneath a shingle. 65

For the purpose of illustrating my invention I have shown in the accompanying drawings one form thereof which is at present preferred by me, since the same has 70 been found in practice to give satisfactory and reliable results, although it is to be understood that the various instrumentalities of which my invention consists can be variously arranged and organized and that my invention is not limited to the precise arrangement and organization of the instrumentalities as herein shown and described. 75

According to the present invention 80 wrought U-shaped channel iron 10 or other metal of channel formation and of desired length, see Figs. 1 and 2; apertured as at 11 for gutter-circle adjustment; and slotted as at 12 for shingle-nail penetration, has that 85 end which is slotted presented to a press for flattening the angles or flanges of the channel iron to reduce the thickness of the channel iron without separating or dividing the channel iron material. While for illustrative purposes the term channel iron 90 will be used herein, obviously I may employ copper, brass or other metal capable of being flattened in a press and in all instances the channel metal employed is of constant cross sectional area. The die 13 employed for 95 the purpose is slightly tapered so that the flanges of the channel iron adjacent that end thereof as is provided with the slots 12 are flattened out substantially flush with the body portion of the channel iron, see Fig. 6, 100 and thereafter are gradually less disturbed. This provides a generally tapered effect 14 considered in side elevation, see Fig. 4. Considered in plan, see Fig. 5, the flattened 105 end 15 is appreciably wider than is the opposite end of the channel iron and this width gradually decreases as the height of the tapering angles or flanges increase. There is thus provided, considered in plan, 110 a generally tapered effect. In other words the portion of the channel iron having the slots 12 therein is tapered longitudinally

and transversely considered. The tapered construction terminates short of that part of the channel iron provided with the apertures 11. The channel iron is now subjected to a bending operation at 16 well understood in the art, to provide a finished eaves trough shank, see Fig. 7. By the above method of manufacture shearing of angles or flanges is eliminated; no "stock" is taken from the channel iron material; the cost of manufacture is reduced; the speeding up of work enhanced; care in presenting angles or flanges for change in contour reduced to a minimum; and a more efficient and generally improved shank provided. Another advantage resides in the fact that the flattened and reduced end of a shank may be more readily inserted beneath a roof shingle 17, see Fig. 8; because it is now relatively thin and free of projecting portions; angles or flanges. Another advantage of having the penetrating end of a shank flattened is that when shingles are being nailed to place they are less likely to split than is the case when secured over a shank having continuous angles or flanges even though they be sheared.

It will now be apparent that I have de-

vised a novel and useful construction which embodies the features of advantage enumerated as desirable in the statement of the invention and the above description and while I have in the present instance shown and described the preferred embodiment thereof which has been found in practice to give satisfactory and reliable results, it is to be understood that the same is susceptible of modification in various particulars without departing from the spirit or scope of the invention or sacrificing any of its advantages.

What I claim is:

As a new article of manufacture an eaves trough shank of channel formation having a constant cross-sectional area the angles or flanges of which at one end are mutilated to provide a relatively flat, broadened condition which angles or flanges thereafter are less mutilated and taper toward the opposite end of said shank to provide a substantially wedge-shaped end for ready insertion beneath a roof shingle.

In testimony whereof, I have hereunto signed my name.

MATTHEW RUSSELL BERGER
